UNITED STATES PATENT OFFICE.

JOSEPH A. RAYDER, OF PHILADELPHIA, PENNSYLVANIA.

PHONOGRAPH-AMPLIFIER.

1,400,985.

Specification of Letters Patent. Patented Dec. 29, 1921.

Application filed January 17, 1921. Serial No. 437,654.

To all whom it may concern:

Be it known that I, JOSEPH A. RAYDER, a citizen of the United States, residing at Philadelphia, in the county of Philadelphia and State of Pennsylvania, have invented new and useful Improvements in Phonograph-Amplifiers, of which the following is a specification.

This invention relates to phonographs or talking machines and it has more particular reference to cabinets therefor, the main object being to provide a cabinet with which is combined an extensible horn, said extensible horn being so constructed and arranged that when in use it is properly supported while an uninterrupted flare is presented for the amplification of the sounds reproduced by the travel of the tone arm over the record.

Another object of my invention is to provide a combined phonograph cabinet and extensible horn whereby the volume and distinctness of the sounds produced are greatly enhanced.

A further object of this invention is to provide a novel means associated with the amplifier or extensible horn whereby the tones or sounds reproduced from the record are more evenly distributed and at the same time greatly clarified in quality; in other words, an important feature resultant to my novel construction of amplifier and extensible horn is that the customary metallic sounds associated with phonographic reproductions is practically eliminated.

With the foregoing primary and other objects in view as will later on become more apparent as this description proceeds, my invention consists essentially in the novel features of construction, combination and arrangement of parts hereinafter fully described and more specifically defined by the appended claims.

In the further disclosure of the invention reference is to be had to the accompanying sheets of explanatory drawings constituting a part of this specification, and in which like characters of reference designate the same or corresponding parts in all the views.

Figure 1— is a side elevation of my improved phonograph cabinet and extensible amplifier or horn, partly broken away and in section to better disclose the extensible horn in collapsed or closed in position.

Fig. 2— is a front elevation of the cabinet drawn to a reduced scale.

Fig. 3— is a similar side elevation to Fig. 1, but showing the extensible amplifier or horn in fully extended position.

Fig. 4— is a sectional plan taken approximately on the line 4—4 in the preceding figure.

Fig. 5— is a front view looking directly into the inner section of the extensible amplifier or horn and drawn to an enlarged scale; and,

Fig. 6— is a detail side view of a part hereinafter more particularly defined.

Referring now more particularly to the drawings the numeral 10 designates the phonograph cabinet generally which is supported on feet 11 and divided into upper and lower compartments 12, 13, respectively, the latter of which is provided with spaced shelves 14 for the storage of records, side doors 15 furnishing a closure thereof. The upper compartment 12 is closed in by a cover or crown 16 provided with a surrounding lip 17 whereby a dust-proof joint is insured, and the back 18 of said upper compartment is rabbeted and made removable for the purpose hereafter explained. Hinged doors 19 close in the front of the upper compartment 12.

Arranged within the upper compartment 12 is a box-like structure 20 conveniently rectangular in configuration and said structure is of dimensions to be a sliding fit between the side walls 21, runners 22 being provided for co-operation grooves 23 where- by the box-like structure 20 is guided as well as limited in its movement. Supporting legs 24 having appropriate casters 25 thereunder are fitted beneath the front of the box-like structure 20 for supporting same when in extended position as shown in Fig. 3, and it is to be particularly noted that when the said structure 20 is in closed position the legs 24 lie snugly against the front of the cabinet 16 while the doors 19 completely close in the front of the box-like structure within the upper compartment 12.

Supported within the box-like structure 20 beneath the upper wall thereof is the motor 26 of appropriate pattern and the spindle 27 thereof supports the turn-table 28 on which the record 29 is placed.

The tone arm proper comprises two sections 30, 31, the former of which carries the reproducer 32 while said sections are connected together by a knuckle joint or universal 33. Supported by a horizontally dis-

posed brace 34 conveniently secured to the side walls 21 is a depending elbow section 35 which is flanged at its upper part to house a ball or anti-friction bearing 36 for 5 the inner end of the tone arm section 31 and at the lower end of said elbow section 35 I attach the inner portion 37 of an amplifier as by a flanged connection 38. This inner portion 37 is preferably flared outwardly 10 from a circular end where it is connected to the elbow-section 35 to elliptical formation at its outer end 37^a where it is stiffened or strengthened by a circumscribing band 39. In connection with the amplifier section or 15 inner portion 37 I preferably employ the tone distributing means illustrated and which comprises a dished member 40 provided with a threaded shank 41 for adjustable engagement in the wall of the afore- 20 said elbow section 35, said dished member 41 being tessellated or corrugated at 42. To each of the tessellations or corrugations 42 on the dished member 41, I attach the inner end of a tone conveying wire or string 43, 25 the free end whereof is connected to an appropriate key or peg 44 passing through the aforesaid circumscribing band 39 and outer end 37^a of the amplifier portion 37, and it will be readily understood that in this manner 30 I provide a simple and effective means whereby the strings 43 can all be accurately tuned to the requisite and same pitch whereby the sound waves traversing the tone arm sections 30, 31, and elbow 35 when repro-

35 duction is taking place will be evenly distributed about and around the amplifier portion 37. Furthermore, I find that by the use of the distributing means just described the usual metallic tone is to all ordinarily 40 discernible purpose entirely eliminated, while the tonal effect is considerably enriched and rendered more approximate to the sounds recorded.

Built into the aforesaid box-like structure 45 is the mouth or outer portion 45 of the amplifier and it is made of a cross section conforming to the outer end 37^a of the inner amplifier section 37, so that when said

parts are extended as shown in Fig. 3 the circumscribing band 31 engages an inner lip 50 or flange 46 whereby an unbroken and gradual amplification of sound results as will be clearly understood by those skilled in the art to which this invention appertains.

In use and assuming the cabinet is closed up as shown in Figs. 1 and 2, the user first opens the doors 19, and draws out the box-like structure 20—which is supported by the legs 24—to its full extent as shown by 60 Figs. 3 and 4. A record 29 is placed on the turntable 28 and the tone arm section 30 swung out from the position shown in dotted lines in Fig. 4 to the full line position shown in Figs. 3 and 4. The motor 26 is started 65 and it will be readily seen that reproduction from the record 28 will take place in the ordinary and well known way, with the added advantages of increased amplification of sound, and due to the employment of the 70 strings 43 an enhanced and clearer tonal effect will result.

While I have described and shown the best known form of my invention at present known to me I wish it clearly understood 75 that various changes and other combinations thereof may be readily evolved to adapt said invention to different types and forms of talking machines, and it is intended to hereby include all such reasonable 80 modifications as fairly fall within the scope of the appended claims.

Having described my invention what I claim as new and desire to secure by Letters Patent is—

- 35 1. In a phonograph, an amplifier, strings disposed about its inner surface and means for adjusting said strings simultaneously.
2. In a phonograph, an amplifier, a dished member adjustably mounted at the inner 90 end of the amplifier, pins at the outer end thereof and strings having their ends connected with the dished member and the said pins.

In testimony whereof I affix my signature, 95
JOSEPH A. RAYDER.
